[57] CLAIM

I claim the ornamental design for a high heel shoe with ergonomic toe, as shown and described.

DESCRIPTION

FIG. 1 is a top plan view of the high heel shoe with ergonomic toe embodying the design of the present invention.

FIG. 2 is a right side view in elevation of the high heel shoe with ergonomic toe.

FIG. 3 is a left side view in elevation of the high heel shoe with ergonomic toe.

FIG. 4 is a bottom plan view of the high heel shoe with ergonomic toe.

FIG. 5 is a front view in elevation of the high heel shoe with ergonomic toe.

FIG. 6 is a rear view in elevation of the high heel shoe with ergonomic toe.
